UNITED STATES PATENT OFFICE.

ETTA NETZHAMMER, OF ST. LOUIS, MISSOURI.

DISHWASHING MACHINE.

Application filed September 16, 1926. Serial No. 135,715.

This invention relates to improvements in dish washing machines, and has for one of its principal objects the provision of means whereby dishes and similar objects may be 5 readily and conveniently washed and cleansed in an economical and efficient manner.

One of the important objects of this invention is to provide, in a dish washing machine, the combination of means for both washing and drying dishes and similar objects, while at the same time providing for a clean and sanitary method of such operation.

Other and further important objects of the invention will be apparent from the disclosures in the accompanying drawings and following specification.

The invention, in a preferred form, is illustrated in the drawings and hereinafter more fully described.

In the drawings:

Figure 1 is a vertical section of the improved dish washing machine of this invention.

Figure 2 is a similar vertical section showing the dish supporting colander in raised drying position.

Figure 3 is a detail view showing one of the mop supporting elements.

Figure 4 is a perspective view of a mop used in the machine.

Figure 5 is a detail view illustrating the construction of the mop supporting cam, and

Figure 6 is a detail view showing the means for locking the dish supporting colander in raised position.

As shown in the drawings:

The reference numeral 10 indicates generally the casing of the improved dish washing machine of this invention, having mounted therein an operating motor 12 which drives a shaft 14, the shaft having in

turn mounted thereon a gear 16, which meshes with a longitudinal gear 18 mounted on a central drive shaft 20, from which the dish supporting colander 22 is supported, and whereby this colander is rotated. The 50 colander itself is positioned in a water tank or the like 24, which is provided with a spigot 26, whereby the same may be readily emptied, if desired.

A pulley 28 is also mounted on the shaft 55 14 and by means of a belt 30 drives the

corresponding pulley 32, which operates an integral offset cam 34, and upon the face of this cam rides the lower end of a mop operating shaft 36 mounted in suitable sleeves 38 on the casing 10, and having adjustably mounted on its upper end a mop supporting bracket 40 from which depend 60 mop holders 42 having mops 44 removably attached thereto. The mop holders 42 may be attached to the brackets 40 in any convenient manner, as by winged nuts or by bolts.

The mops 44 are constructed with upper encircling bands 46 whereby they may be readily attached and detached to and from 70 the brackets 42.

As shown in Figure 2, the dish supporting colander 22 may be raised from the water in the tank 24 by the operation of a lever 50, which in turn lifts the shaft 20 into raised 75 position, whereby the dishes in the colander 22 may be conveniently dried, new dry mops 44 being at the same time attached to the mop holders 42. The operating lever 50 is adapted to be locked in colander raising 80 position by means of a latch or the like 52 forming part of the casing support 10, as best shown in detail in Figure 6.

It will be evident that herein is provided a means for economically and conveniently 85 washing dishes or the like, with a minimum of trouble and inconvenience, while at the same time there is provided suitable means for disposing of the wash water and the maintenance of the entire apparatus in a 90 clean, sanitary condition at all times.

I am aware that many changes may be made and numerous details of construction varied throughout a wide range without departing from the principles of this invention, and I therefore do not purpose limiting the patent granted hereon otherwise than as necessitated by the prior art.

I claim as my invention:

1. In a dish washing machine, the combination of a dish water tank, means mounted in said tank for supporting dishes in both raised and lowered positions, said means comprising a central vertical shaft extending through the bottom of the tank, a colander 100 in the tank suspended from the top of said shaft, manually operated means associated with the lower end of said shaft for raising the colander in the dish water tank, and means for rotating the colander in both 105 110

raised and lowered positions, said means comprising a motor driven gear and a longitudinal gear on the shaft in mesh with said motor driven gear.

5. 2. In a dish washing machine, the combination of a dish water tank, means mounted in said tank for supporting dishes in both raised and lowered positions, said means comprising a colander, and means for rais-

10 10 ing the colander in the dish water tank, together with additional means for rotating the colander in both raised and lowered positions, and a plurality of mops reciprocatively mounted with respect to the dish

15 supporting colander.

3. In a dish washing machine, the combination of a dish water tank, means mounted

in said tank for supporting dishes in both raised and lowered positions, said means comprising a central shaft, a colander on the shaft, a dish water tank, a manually operated lever for raising the colander from the dish water tank, together with a longitudinal gear on the shaft for rotating the colander in both raised and lowered position, and a plurality of mops reciprocatively mounted with respect to the dish supporting colander, and means for supporting said mops in operating position, said means comprising cam operated brackets and hooks on the ends of the brackets adapted for the removable positioning of the mops.

In testimony whereof I affix my signature.

ETTA NETZHAMMER.
